UNITED STATES PATENT OFFICE

166,908

CHILD'S CHAIR

Francis E. Ducey, Phoenix, Ariz.

Application February 23, 1951, Serial No. 14,299

Term of patent 14 years

(Cl. D15—1)

To all whom it may concern:

Be it known that I, Francis E. Ducey, a citizen of the United States of America, residing at Phoenix, in the county of Maricopa, and State of Arizona, have invented a new, original, and ornamental Design for Child's Chair, of which the following is a specification, reference being had to the accompanying drawing, forming part thereof.

In the drawing,

Fig. I is a plan view of a child's chair showing my new design,

Fig. II is a side elevational view, and

Fig. III is a perspective view.

The design is particularly characterized by the handles and the skeleton-like frame supporting the seat.

I claim:

The ornamental design for a child's chair, substantially as shown and described.

FRANCIS E. DUCEY.
